UNITED STATES PATENT OFFICE.

WILLIAM H. WILKINSON, OF ST. LOUIS, MISSOURI.

DESIGN FOR A COOKING-STOVE.

SPECIFICATION forming part of Design No. 16,450, dated December 29, 1885.

Application filed June 27, 1885. Serial No. 170,014. Term of patent 14 years.

To all whom it may concern:

Be it known that I, WILLIAM H. WILKINSON, a citizen of the United States, residing at the city of St. Louis, Missouri, have invented and produced a new and original Design 5 for Cooking-Stoves, of which the following is a specification, reference being had to the accompanying engraving, forming part thereof, and showing the newly-designed stove in perspective.

This design embraces several new and distinctive parts and combinations of parts which go to make up the whole design, as herein-after described.

15 The stove in its general outline is cubical, and it usually is provided at its front with a hearth and at its opposite end with a water-reservoir.

20 The leading feature of the design appears upon the oven-door A of the stove. It consists, mainly, in the two combinations of the pair of griffins B B and the bunch of grapes C, which is interposed between the two griffins, and above all is the semicircular bar D.

25 An additional feature of the design is the representation upon each of the hot-closet doors E E, consisting of the griffin F, whose body f is not provided with legs, but is extended to form a scroll, f', in which may be inclosed the 30 bunch of grapes f'.

Other features are the pot of fire G upon the fire-place door H and the head I below the door H; also the recumbent griffins J J upon opposite sides, respectively, of the pipe-collar K.

All of these features appear in relief upon the side of the stove.

I claim—

1. In a design for a stove, the ornamentation of the doors E E, consisting of the griffins F F, 40 having their bodies extended to form the scrolls f', as shown and described.

2. In a design for a stove, the ornamentation consisting of the griffins B B upon the door A and the interposed bunch of grapes, as shown 45 and described.

3. In a design for a stove, the shape and ornamentation of the panels adjacent to the pipe K, the same being that of recumbent griffins J J, as shown and described.

4. In a design for a stove, the ornamentation consisting of the griffins B B upon the door A, the griffins F F, configured as shown, and the recumbent griffins J J adjacent to the pipe K, as described.

WILLIAM H. WILKINSON.
